UNITED STATES PATENT OFFICE.

DEWEY H. BITNEY, OF ALBION, MICHIGAN, ASSIGNOR TO UNION STEEL PRODUCTS COMPANY, OF ALBION, MICHIGAN.

STRUCTURAL UNIT.

Original application filed November 25, 1925, Serial No. 70,865. Divided and this application filed August 6, 1926. Serial No. 127,573.

This invention relates to improvements in structural units of the type illustrated in my application for Letters Patent Serial No. 70,865, filed November 25, 1925, this application being a division thereof.

The main object of this invention is to provide an improved structural unit for beams, joists and the like which is adapted to be handled and installed as a complete unit and is well adapted to withstand the stresses to which it is subjected and constituting means for supporting the reinforcing bars.

Objects pertaining to details and economies of my invention will definitely appear from the detailed description to follow. The invention is clearly defined and pointed out in the claims.

A structure embodying the features of my invention is clearly illustrated in the accompanying drawing forming a part of this application, in which:

Fig. 1 is a side elevation of a structural unit embodying my improvements.

Fig. 2 is a vertical section on a line corresponding to line 2-2 of Fig. 1.

Fig. 3 is a detail sectional view showing one relation of my improved structural unit in use, the unit being sectioned as in Fig. 2.

Referring to the drawing my improved structural unit comprises a plurality of U-shaped stirrup elements 1 disposed in spaced relation, these elements being formed of rods bent to U-shape and having, in the embodiment illustrated, laterally turned ends 2. These stirrup elements are rigidly secured upon the longitudinal spacing and supporting rods 3, being in practice secured to these rods by electrically welding thereto.

These rods 3 have downwardly disposed loops 4 therein providing supporting legs for the unit, there being a leg adjacent each end and one or more intermediate legs, according to the length of the unit. The embodiment illustrated has three legs.

The stirrup members are further supported in upright position and in properly spaced

relation by means of the side longitudinal rods 5 which are rigidly secured to the arms of the stirrup members adjacent their upper ends by welding thereto.

The hooks or laterally turned ends 2 are, in the embodiment illustrated, disposed longitudinally of the unit so that the transverse reinforcing bars 6 may be engaged under the same, the longitudinal reinforcing bars 7 being arranged in the stirrups as shown in Fig. 3.

By arranging the longitudinal rods 5 on the outside as shown in the accompanying drawing, a plurality of units may be nested quite compactly.

My improved reinforcing units are economical to produce and are capable of very wide use, being quickly and easily placed in the forms and the parts being so secured together that likelihood of errors arising from carelessness or inattention of the workman are minimized. The parts are so disposed that the unit is well adapted as a reinforcing element as well as a supporting or positioning element for the reinforcing bars.

Having thus described my invention what I claim as new and desire to secure by Letters Patent is:

A structural unit comprising a plurality of U-shaped elements disposed in vertically spaced relation, and a pair of longitudinally disposed supporting rods disposed below and welded to the bottom cross piece of said U-shaped elements, said supporting rods having downwardly projecting loops therein disposed between certain of said U-shaped elements providing supporting legs for the unit and longitudinal side rods welded to said U-shaped elements adjacent their upper ends, said bottom and side longitudinal members coacting to rigidly support said U-shaped elements in spaced upright relation.

In witness whereof I have hereunto set my hand.

DEWEY H. BITNEY.
